ATTORNEY

UNITED STATES PATENT OFFICE

WILLIAM G. CALKINS, OF DETROIT, MICHIGAN, ASSIGNOR TO CHRYSLER CORPORATION, OF DETROIT, MICHIGAN, A CORPORATION OF DELAWARE

PISTON

Application filed April 20, 1928. Serial No. 271,617.

This invention relates to pistons and more particularly to a composite piston having a head section of a metal of a given coefficient of expansion and a skirt section of a metal of 5 a different coefficient of expansion.

In the manufacture of pistons it is desirable to reduce the weight to a minimum thereby minimizing bearing pressures and reducing vibration. An aluminum alloy piston is 10 light in weight but due to the high coefficient of expansion of the aluminum considerable difficulty has been experienced with the skirt section because of its expansion at high temperatures. It is desirable therefore to make 15 the skirt section of a metal, such as cast iron, having a less coefficient of expansion than the aluminum alloy. A composite piston having an aluminum alloy head section and a cast iron skirt section is sufficiently light in 20 weight and maintains the advantages of the full cast iron piston.

Heretofore, the connection between the head section and the skirt section of a composite piston has presented several problems; 25 the conduction of heat from the head section to the skirt, mechanical distortion of the skirt section due to the thermal expansion of the head section, and the thermal expansion of the connecting means where such is used.

30 It is an object of this invention to provide a piston head section having a high coefficient of expansion and securing thereto a full skirt section having a lower coefficient of expansion; the head section also having a high rate 35 of heat conductivity in order to maintain low head temperatures permitting the use of high compression ratios and high speeds.

Another object of the invention is to unite 40 the head section with the skirt section in such a manner that the head section is mechanically free from the skirt section at the outer periphery so that thermal expansion of the head section does not cause mechanical distortion of the skirt section. The head section is thermally insulated from the skirt section in so far as practical.

A further object of the invention is to 45 form the piston pin-bosses integral with a full cast iron skirt so that the thermal heat 50 conduction and thermal expansion of the

head section does not effect the bearing conditions with reference to clearance and distortion.

Another object of the invention is to fasten a head section having a high coefficient 55 of expansion to a skirt section having a lower coefficient of expansion by a means provided to compensate for the differential expansion rate of the two members.

Other objects and advantages will more 60 fully appear from the following description taken in connection with the accompanying drawings in which:

Fig. 1 is a vertical sectional view of my 65 improved piston.

Fig. 2 is a view corresponding to Fig. 1 showing a modification of my invention.

Fig. 3 is a perspective view of a compensating member utilized in my invention.

Referring to the drawings, I have shown 70 a piston having a head section 10 made of a metal having a high coefficient of expansion and a high rate of heat conductivity, preferably cast from an aluminum alloy. The central portion of the head section 10 is provided with a boss 12 having an opening 14 to receive a securing means such as a bolt 16. A counterbore 18 is provided to receive the head 20 of the bolt 16. The outer periphery 75 of the head section is provided with an annular flange 22 which receives piston rings 24.

Improved results have been found by the 80 particular combination and arrangement 85 of rings shown in the drawings. The upper ring comprises a two part ring 24, each part having adjacent flanges 26 overlapping a tongue 28 in the ring groove 30. The central ring 32 is provided with a groove 34 at its lower outer corner. The lower ring 36 90 is provided with radial openings 38 through which lubricant may pass from the cylinder wall to an opening 40 in the flange 22 where it may drain back into the crank case. The upper ring 24 is ideal for a compression ring 95 as the compression forces find their way into the ring groove 30 and force the rings outwardly against the cylinder wall.

The central ring 32 scrapes the lubricant 100 from the cylinder wall and the lower ring

36 permits the lubricant to drain away from the cylinder wall.

5 The skirt section comprises an inverted cup shaped member having a head portion 42 and a full cylindrical portion 44. The head portion 42 is provided with a plurality of openings 46 which reduce the weight of the skirt section and permit the lubricant to be drained out of the head section. A central opening 48, in axial alignment with the opening 14, receives the threaded end of the bolt 16.

10 The skirt section is preferably made from a nickel-chrome alloy cast iron or a high tensile pearlitic iron. This metal has a low coefficient of expansion as compared with the aluminum alloy head and the piston skirts may be made with slight clearances. A full cylindrical skirt provides a cross head 15 guide in all directions and is uniform in its bearing characteristics.

15 Wrist pin bosses 50 are formed integral with the skirt section 44 and are independent of the head section so that the thermal expansion of the head section does not mechanically distort the bosses 50.

20 The head section is fastened to the skirt section by a means which compensates for the differential expansion rates of the two metals. In the form shown in Fig. 1 a steel bolt 16 is used, extending through the aligned openings 14 and 48. A concave washer 52, preferably made of spring steel, is placed over the threaded end of the bolt 25 16 with its outer periphery in engagement with the under surface of the head portion 42 and a nut 54 screwthreaded on the bolt 16 engages the central portion of the concave member 52. A cotter key 56 prevents 30 turning the nut 54. The form shown, however, is preferable as it does not unbalance the piston.

35 As the head section expands, the bolt 16 is carried with the upper outer surface of the head section and slides through the opening 48 in the head portion 42 of the skirt section compressing the resilient member 52. If the parts were rigidly secured at this 40 point, the expansion of the head section 50 would cause the bolt or the head portion to break or distort.

45 The outer surface of the boss 12 may extend slightly beyond the outer surface of the flange 22 so that the point of contact between the head section and the skirt section is at the center. The important thing is that the head 55 is mechanically free from the skirt section at the outer periphery so that the head section expands radially independent of the skirt.

60 The head section is practically thermally insulated from the skirt so that there is but slight thermal expansion of the skirt and no mechanical distortion of the skirt due to the 65 thermal expansion of the head section.

If desired the head section may be forged from a high strength aluminum alloy and a threaded projection 60 formed on the end of the boss 12, as shown in Fig. 2. In this form the differential expansion between the two metals is less and there is less movement of the resilient member 52. A shoulder 62 is provided on the projection 60 to form a stop for the central portion of the resilient member 52 or the nut 54 so that the parts may not be drawn together to prevent the movement of the projection 60 in the opening 48. This same plan may be followed on the construction shown in Fig. 1. On the other hand, if desired, the stop may be omitted, the nut screwed in until the center of the washer bottoms on the head 42 and then the nut may be backed off a pre-determined amount so as to leave a certain tension on the spring washer and a certain clearance between the center of the washer and the bottom of the head 42.

70 It will be obvious that various changes may be made in the arrangement, combination and construction of the various parts of my improved device without departing from the spirit of my invention and it is my intention to cover by my claims such changes as may reasonably be included within the scope thereof.

75 What I claim is:

1. A piston of the class described comprising, a head section having a given coefficient of expansion, an annular flange at the outer periphery of said head section, a boss on the axial line through said head section, said boss having its outer surface extending slightly beyond the outer surface of said flange, a skirt section having a lower coefficient of expansion than said head section, wrist pin bearings and a flat head portion integral with said skirt section, and means carried by said boss including an expansible connecting member for yieldably securing said head section and said skirt section together.

80 2. A piston of the class described comprising, an aluminum alloy head section, an iron alloy skirt section having a flat head portion provided with a plurality of openings one of which is on the axial line through said piston, a central engaging portion on said head section adapted for engagement with the upper surface of the skirt head portion, a member having a diameter less than the diameter of the central engaging portion projecting from said engaging portion to be received in the axial opening in the head portion, a screwthreaded member on the outer end of said projection, and a spring steel member between said screwthreaded member and the lower surface of the head portion of said skirt section.

85 3. A piston of the class described comprising, a head section having a given coefficient of expansion, a skirt section having a lower coefficient of expansion, an end wall on said

skirt section having a central opening therein, an annular flange at the outer periphery of said head section free for radial expansion with respect to the outer periphery of said skirt section, a central portion on said head section extending beyond the outer extremity of said flange adapted for engagement with the upper surface of the end wall of said skirt section, a member projecting from said engaging portion to be received in the central opening in said end wall, a screw-threaded member on the outer end of said projection, and a spring steel member between said screwthreaded member and the lower surface of the end wall of said skirt portion.

4. A piston including a head part having a peripheral flange and a central boss extending slightly beyond the outer extremity of said flange, a skirt part having an end wall bearing against the end of said boss, the extremity of said flange being held against contact with said end wall during thermal expansion of said flange by the corresponding expansion of said boss, and means on said boss coacting with said end wall for securing said skirt and head parts together.

5. A piston including a head part having a peripheral flange and a central boss extending slightly beyond the outer extremity of said flange, a skirt part having an end wall bearing against the end of said boss, the extremity of said flange being held against contact with said end wall during thermal expansion of said flange by the corresponding expansion of said boss, a stem on said boss extending through an aperture in said end wall, and a yieldable member on said stem engaging the inner side of said end wall and yieldably securing said head and skirt parts together.

WILLIAM G. CALKINS.
